APPARATUS FOR DISTILLING FATTY ACIDS

Filed Dec. 16, 1925

UNITED STATES PATENT OFFICE

HERMANN BOLLMANN, OF HAMBURG, GERMANY

APPARATUS FOR DISTILLING FATTY ACIDS

Application filed December 16, 1925, Serial No. 75,744, and in Germany February 2, 1925.

This invention relates to apparatus for distilling fatty acids. In the distillation of fatty acids in column apparatus on the counter current principle, in which the fatty acids are led, in a finely divided state, in countercurrent to superheated steam conducted upwardly, there exists the danger that the steam loaded with the volatile constituents of the fatty acids may sink downwardly again. This danger can be obviated by the apparatus forming the subject of the invention.

According to the invention the apparatus consists of a column made, for example, from chamotte, surrounded by a metal jacket and adapted to be subjected to a vacuum. The column, which is filled with a retarding filling, for example, Raschig rings, is provided with a number of intermediate partitions, each of which has a substantially central opening or openings. By means of the reduction of cross section effected by these intermediate partitions provided with openings, an increase in the velocity of flow of the steam is obtained at the levels of the partitions, (as compared with the velocity between the partitions) and the movement in the reverse direction of steam loaded with fatty-acid vapours is thereby prevented.

One example of an apparatus according to the invention is diagrammatically illustrated in the accompanying drawing, wherein the apparatus is shown as being constituted by a column 1, made preferably of chamotte surrounded with a metal jacket 8, which is adapted to be subjected to vacuum and is provided with a number of intermediate partitions 2 having central openings as indicated in the drawing. Steam at, for example, 280° C. enters from below by the pipe 3 while the fatty acids to be distilled are introduced into the column 1 through the pipe 4 and trickle down in a finely divided state over the retarding filling of, for example, Raschig rings (not shown) present therein. The vapors of the fatty acids and steam, leave the apparatus by the pipe 6, while the residue (containing non-vaporizable matters) may be drawn off through the pipe 5.

I claim:—

In an apparatus for distilling fatty acids, the combination of a column comprising a chamber, partitions spaced at intervals across said chamber and defining a plurality of compartments, said partitions having such construction as to prevent the substantial accumulation of liquid thereon and having free openings near the center of each of the same for permitting the passage of vapor, the remaining parts of said partition being impervious to the passage of vapor, means for introducing fatty acid near the top of said column, means for withdrawing vapors from said column, and means for introducing superheated steam near the foot of said column, said openings being unprovided with hoods.

In testimony whereof I affix my signature.

HERMANN BOLLMANN.
